UNITED STATES PATENT OFFICE

159,302

SHOE SOLE

Adolf Steinhilber, Rock Island, Ill., assignor to
The Servus Rubber Company, Rock Island, Ill.,
a corporation of Illinois

Application October 21, 1949, Serial No. 5,642

Term of patent 14 years

(Cl. D7—5)

To all whom it may concern:

Be it known that I, Adolf Steinhilber, a citizen of the United States, and a resident of Rock Island, in the county of Rock Island, State of Illinois, have invented a new, original, and ornamental Design for a Shoe Sole, of which the following is a specification, reference being had to the accompanying drawing, forming a part hereof.

Fig. 1 is a bottom plan view of a shoe sole, showing my new design.

Fig. 2 is a side elevation of Fig. 1.

Fig. 3 is a transverse section taken on the line 3—3 in Fig. 1.

Fig. 4 is a transverse section taken on the line 4—4 in Fig. 1.

Fig. 5 is a transverse section taken on the line 5—5 in Fig. 1.

I claim:

The ornamental design for a shoe sole, as shown.

ADOLF STEINHILBER.
